DESIGN FOR AN ELECTRIC TRANSFORMER

James A. Comstock, Cleveland, Ohio, assignor to
The Acme Electric & Manufacturing Com-
pany, Cleveland, Ohio, a corporation of Ohio

Application September 11, 1935, Serial No. 58,509

Term of patent 14 years

To all whom it may concern:

Be it known that I, James A. Comstock, a citizen of the United States, residing at 1730 Crawford Road, Apt. 316, in the city of Cleveland, county of Cuyahoga, and State of Ohio, have invented a new, original, and ornamental Design for an Electric Transformer, of which the following is a specification, reference being had to the accompanying drawing, constituting a part thereof.

Figure 1 is a side elevational view of an electric transformer showing my new design.

Figure 2 is a left hand end elevational view of the electric transformer shown in Figure 1, and

Figure 3 is a right hand end elevational view of the electric transformer shown in Figure 1.

I claim:

The ornamental design for an electric transformer substantially as shown.

In testimony whereof, I have hereunto subscribed my name this 10th day of September, 1935.

JAMES A. COMSTOCK.
